(57) **CLAIM**

The ornamental design for an irrigation device, as shown and described.

DESCRIPTION

FIG. 1 is a perspective view of a top and a rear side of the ear irrigation device;

FIG. 2 is a side elevation view of a first side thereof;

FIG. 3 is a side elevation view of a rear side thereof;

FIG. 4 is a side elevation view of a second side thereof;

FIG. 5 is a side elevation view of a front side thereof;

FIG. 6 is a top view thereof;

FIG. 7 is a bottom view thereof;

FIG. 8 is a perspective view of an alternative embodiment of the subject invention;

FIG. 9 is a side elevation view of a first side thereof;

FIG. 10 is a side elevation view of a rear side thereof;

FIG. 11 is a side elevation view of a second side thereof;

FIG. 12 is a side elevation view of a front side thereof;

FIG. 13 is a top view thereof; and,

FIG. 14 is a bottom view thereof.

The broken lines in FIGS. 7 and 14 are for illustrative purpose only and form no part of the claimed design.
